WILLIAM A. HYLAND, OF EAST MOLINE, ILLINOIS, ASSIGNOR TO DEERE & COMPANY,
OF MOLINE, ILLINOIS, A CORPORATION OF ILLINOIS

MOLD

Application filed January 19, 1931. Serial No. 509,582.

The present invention relates to an improved method of and means for constructing wheels and is more particularly directed to a mold for casting hubs thereon. This mold is best adapted for casting the hub of the common type of spoked wheel most generally used in connection with agricultural implements, although the mold can be utilized for casting the hubs of any type of wheel where-
10 in the spokes are initially assembled to the rim and the hub cast between the suspended inner ends of the spokes, embedding the latter therein.

In the fabrication of wheels of this type, it has been the customary practice to provide a sectionalized metal chill comprising two halves of a ring for forming the outer contour of the hub between the two sets of spokes, but, a chill of this kind could not be utilized
20 to cast scallops on the portion of the hub between adjacent spokes nor between the two sets of spokes. This difficulty is encountered for the obvious reason that the divergence of the adjacent spokes in each set would necessarily require scallops diverging from the hub in line with each of the respective spokes, from which it is evident that the half-sectional metal chills could not be radially removed from the hub. Heretofore, in order to cast
25 scallops on the hub for encasing the ends of the spokes, the practice has been to provide a circular sand core which is disposed substantially centrally between the two sets of spokes and between sectionalized metal chills. After casting the hub, the sand core is broken away, allowing the sectional chills to be moved axially
30 inwardly to clear the scallops, and then radially from the hub to be removed from between the spokes.

40 This method of casting the hubs is not very satisfactory because, for one reason, although a considerable portion of the mold comprising the metal chills can be used repeatedly, every mold requires a new sand core, the use of which, both in setting up and disassembling the mold, requires much time and adds to the cost of fabricating the wheels.

45 One of the main objects of the present invention is to eliminate the use of the heretofore existent sand core from between the two

chills, and to provide a mold comprising sectionalized metal chills capable of casting a hub having scallops thereon, with the ends of the wheel spokes embedded in the scallops.

Another object of the present invention is 55 to so divide the chills that a minimum number of inner chills are used to complete the mold between the two sets of spokes. The number of chills in the present construction is limited to a single pair for forming the 60 inner contours of the scallops cast about the ends of the outer set of spokes, and to one-half as many chills as there are spokes in one set on the wheel for forming the inner contours of the scallops cast about the ends 65 of the inner set of spokes, or vice versa. The foregoing is strictly true for any wheel having an even number of spokes. If a wheel has an odd number of spokes the number of chills for forming the inner contours 70 of the scallops cast about the ends of this set of spokes will be equal to a chill for each pair of spokes as is the case where an even number of spokes are present, but such a mold will require one more chill for ac- 75 commodating the odd spoke, as will be hereinafter more fully described.

80 A further object of the invention is to join the two sets of sectionalized chills of the mold in such a manner that one set will abut the other set on a beveled surface to permit each of the chill members of one set to be drawn radially outwardly without interfering with the scallops formed by those chill members nor with the corresponding 85 spokes.

Further objects and advantages will hereinafter appear in the following detailed description of the mold, reference being had to the accompanying drawings.

90 In the drawings:

Figure 1 is a vertical cross-sectional view through the axis of the mold;

Figure 2 is a plan view taken substantially along line 2-2 of Figure 1, with the cope 95 removed therefrom;

Figure 3 is a plan sectional view taken substantially along the line 3-3 of Figure 1 looking in the direction of the arrows;

Figure 4 is a perspective view of the mold. 100

with the cope and drag removed, illustrating the removal of one of the inner chills from the mold;

Figure 5 illustrates the finished hub after the mold has been removed therefrom;

Figure 6 is a perspective view of one of the inner chill members of the mold which is utilized for forming the inner contours of the scallops cast about the ends of the inner set of spokes;

Figure 7 is a perspective view of another of the chill members which is disposed adjacent the chill members of Figure 6, and utilized for forming the inner contours of the scallops cast about the ends of the outer set of spokes;

Figure 8 is a perspective view of one of the end chill members that is used for forming the outer contours of the scallops which are cast about the ends of the outer set of spokes; and

Figure 9 is a view corresponding to that shown in Figure 2, illustrating a mold for casting a scalloped hub on a wheel having an odd number of spokes.

Referring now to Figure 1, the mold is shown as assembled about the suspended inner ends of the spokes which are initially assembled with rim 10 of a wheel prior to the pouring of the hub metal. The mold is of a general type comprising cope and drag 11 and 12, respectively, preferably of metal, having sand cores 13 and 14, respectively, disposed therein for forming the end portions of the hub. The purpose of using sand cores such as 13 and 14 to form the end portions of the hub is to obtain softer surfaces at these points and thereby facilitate the machining of the outer faces of the hubs. The use of metal chills in place of the cores 13 and 14 would produce a hard surface which is more difficult to finish, although, if desired, metal chills can be substituted for the sand cores depending upon the particular needs of the wheel manufacturer. A core 15, preferably of sand, extends centrally through the mold and is so shaped as to form the interior axle opening of the hub. One end of the core 15 is seated in the lower sand core 14 within the recess 16, and the other end thereof is held within the opening 17 of the upper sand core 13.

Disposed between the cope and drag and encircling the central core member 15 are a number of sectionalized chills, there being three sets for the composition of the balance of the mold. It is obvious that the total number of chills will vary with the number of spokes, but for the sake of illustration a wheel having a set of six outer spokes 21 and a set of six inner spokes 22 is used as a general example. In a wheel having an even number of inner and outer spokes, chill section 23 is preferably composed of a number of chills 23a equal to one-half the number of spokes

in one set. Therefore, in a wheel as shown in Figures 1 to 5, having six spokes in each set, since the number of chills are one-half the number of spokes in a set, it will be seen that three chills 23a are employed. Adjacent chills 23a are two half-circular chills 24a comprising the second chill section 24 of the mold, the latter members being likewise disposed between the two sets of spokes, as are chills 23a. The third chill section 25 comprises a plurality of chills 25a, and although this section is illustrated as made up of a number of chills, a single circular chill could be utilized. The objection to a single chill, however, is that it may be subject to breakage and for this reason it is desirable to divide this chill section into a plurality of chill pieces such as 25a. The latter chill members complete the mold and form the contour of the hub between the outer set of spokes and the sand core 14.

Referring now to Figure 5, it is to be noted that the finished hub H is provided with a number of scallops 30 and 31, wherein the button heads 21' and 22' of the spokes 21 and 22, respectively, are embedded. Suitable ribs, such as 30' and 31', may be provided for joining the several scallops 30 and the several scallops 31 respectively, to strengthen the hub structure. The scallops 30 and 31 extend radially from the hub H in the direction of the individual spokes, and the aforementioned difficulties heretofore encountered resided in casting the radially disposed scallops. To enable the scallops 30 and 31 to be cast, and to enable the chills 23 and 24 to be removed from between the outer and inner sets of converging spokes after the casting of the hub, a parting surface 32, preferably conical, is provided between the plurality of abutting chill pieces 23a and 24a comprising the two chill sections 23 and 24 of the mold, respectively. This is accomplished by providing the bottom faces of chills 23a with beveled faces 23b sloping downwardly and outwardly from the center of the mold, and by providing chills 24a with complementary sloping surfaces 24b for cooperating with the surfaces 23b of chill members 23a, as best illustrated in Figure 1. The angle of the cooperating sloping surfaces with respect to the axial center line of the hub, is determined by the angle that any one of the inner spokes makes with the same axial center line and must in all cases be equal to the spoke angle, or preferably, should be somewhat greater as shown in the mold illustrated. With a parting plane as above described, it is seen that after the hub has been poured and the cope 11 removed, the chill members 23a can be readily moved radially and downwardly away from the rest of the mold into the space between the outer and inner sets of spokes, and likewise away from scallops 31 and spokes 22, clearing the latter mem-

bers and thereafter allowing each chill 23a to be removed from between any two adjacent diverging inner spokes 22 or adjacent diverging outer spokes 21.

5. Another important cooperating factor for accomplishing the removal of chill section 28, is the manner in which this section is divided, having reference to the plurality of chills 23a. Referring to Figure 6, illustrating one of the chills 23a, it is to be noted that this chill is of a peripheral length equal to one-third of the circumference of chill section 23. Obviously, this is only true when six spokes are present, since, as hereinbefore stated, the number of chills 23a is determined by the number of spokes. However, regardless of the number of spokes, each chill 23a is made to straddle one spoke centrally and to extend to the mid-points of the next adjacent spokes, as will be apparent from the radially extending recesses or semi-circular spoke openings 23c and 23d which receive the spokes. The recesses 23c and 23d form in conjunction with corresponding recesses carried in the cope 11, the openings through which the spokes 22 extend into their designated positions within the mold. The spokes when properly positioned form closures for these openings thereby preventing the molten metal from escaping from within the mold. Directly in line with the recesses or spoke openings 23c and 23d, and extending radially from the virtual axial center point of chills 23a, are indentations or recesses 26 and 26a that are adapted to form the inner contours of the scallops 31 for the inner spokes. The indentation or recess 26 is centrally located in chill member 23a and will completely form the inner contour of one of the scallops, while each of the remaining recesses 26a are adapted to form one-half of the inner contours of the next adjacent scallops since the dividing line between the several chills 23a bisects the end recesses 26a. Obviously, the end recesses 26a of the next adjacent chill members will form and complete the balance of the inner contours of the scallops last referred to, etc. This is best illustrated in Figure 2, wherein the inner ends of two of the spokes have been broken away to clearly show the relationship of the semi-circular openings 23c and 23d, as well as the recesses 26 and 26a. Therefore, by having each chill straddling a spoke and extending to the midpoints of the adjacent spokes, any one of the chills 23a may be removed radially outwardly, after the mold has been poured, along the particular spoke which it straddles and likewise along the completed scallop which is aligned with that spoke. This action naturally draws the spoke openings 23d and recesses 26a away from each of the adjacent spokes and scallops inasmuch as the latter diverge from the spoke straddled by member 23a.

65. From the foregoing description it is seen

that each member 23a on being removed, is drawn outwardly from the mold along the line of a spoke straddled thereby. Likewise, the same chill member is moved substantially downwardly or axially (as viewed in Figures 1 and 4), by reason of the beveled surfaces 23b at the bottom thereof, the latter movement being along an angle at least equal to the angle defined between the spoke and the wheel axis and operating to draw the chill laterally into the space between the two sets of spokes and away from the straddled spoke. This double action permits the chill to be easily removed from the mold and subsequently from between any two adjacent spokes. After the chill members 23a have thus been removed, the balance of the mold can also be readily disassembled.

Referring to Figure 7 illustrating one of the chills 24a, it is to be noted that this member also contains semi-circular spoke openings 24c and recesses 24d in alignment therewith, the latter being adapted to form the inner contours of the scallops for the outer set of spokes. Chill member 24a comprises one-half of the chill section 24 since the latter need only consist of two pieces, although it may consist of more and may be divided in any other desired manner. Section 24 may be formed in only two pieces by reason of the fact that the chill members 24a thereof can be moved axially away from the scallops 30 and spokes 21 which are embedded therein, after chill members 23a have been withdrawn from the mold. Cooperating with chill members 24a are chills 25a which have been hereinbefore referred to. Chills 25a contain semi-circular spoke openings 25b and recesses 25c, both forming the pockets into which the ends of the outer spokes are nested and in which the outer surfaces of the scallops 30 are formed when chills 25a are made to abut chills 24a in the assembled mold. Chill section 25 is disposed within an opening 35 of the drag 12 and is seated adjacent the sand core 14.

Having described the mold and its component parts, the assembling and disassembling thereof is accomplished as follows: The drag 12 is placed on any suitable support or gauge table having means thereon for centering the drag with respect to the rim 10 containing the free ends of the spokes, so that the hub will be cast with its shaft opening in the exact center of the finished wheel. Sand core 14 is next dropped into place within the drag, followed by the chills 25a. It is to be noted that the drag is provided with pairs of radially extending ears 40, and links or clamping arms 36 are pivotally carried on bolts 37, the latter being supported by ears 40. At the present stage of assembly, the links are dropped downwardly or horizontally, depending on the type of table used for supporting the mold and wheel

rim. The purpose of the links or clamping arms will presently be referred to. One of the chills 25a has a projecting lug 38 which engages within the opening 39 in the drag. In this manner the chill pieces 25a are definitely positioned and consequently the spokes will also be disposed in certain fixed positions with respect to the drag. From this it is apparent that the spokes of the wheel rim will be disposed in such a manner as to allow the clamping arms 36 to swing upwardly between the spokes without interference.

When the drag is thus far assembled, with core 14 and chills 25a placed therein, chills 23a and chills 24a are then nested around the free ends of the spokes, and into the respective positions that they subsequently occupy in the assembled mold. The wheel is then placed upon the gauge table so as to bring the chills disposed about the free ends of the spokes into the mold centrally of the circularly disposed upstanding fingers 41, and with the spokes extending radially between said fingers. During the latter step, it is obvious that the wheel rim may be rotated slightly to bring the outer spokes 21 into proper alignment with the spoke openings 25b in chills 25a. Spokes 21 will then enter the openings 25b permitting the mold to be properly closed along the parting line between chills 24a and 25a. At this stage the core 15, which forms the axle opening, is placed into the mold, the lower-end thereof being received by recess 16 in the sand core 14, as best illustrated in Figure 1. The cope 11 is then placed over chill members 23a with the spoke openings contained therein in register with the inner set of spokes, and sand core 13 is finally inserted into recess 29 within cope 11 and about the upper end of the central core 15. The mold is then completely assembled, and the final step is to clamp the several parts of the mold. This is accomplished by swinging the clamping arms 36 into vertical position between pairs of radially extending ears 42 carried by cope 11, the latter having been so located over the spokes in assembling the mold as to cause ears 42 to be in direct alignment with the ears 40 of the drag and consequently with links or clamping arms 36. The clamping arms are provided with openings 50 through which suitable wedges 51 are inserted for the purpose of clamping the several mold parts firmly together, preparatory to the pouring of the mold. The molten metal is poured into the mold through a suitable gate 43 which is formed in the central core member 15, and which is aligned with a cutout 46 in core member 13.

After the hub has been cast and the metal has cooled, wedges 51 are withdrawn to release the clamping arms 36. The wheel is then lifted away from the drag to free chill members 23a and 24a from within the up-

standing fingers 41 of the drag. The wheel and the parts of the mold retained thereby are easily removed from the drag inasmuch as the inner surfaces of the fingers 41 are beveled towards the open side of the drag, and the outer surfaces of chill members 23a and 24a are correspondingly beveled. Chills 25a will remain within the drag with the sand core 14, while the central core 15 is retained within the cast hub H until it is broken out. Upon next removing the upper cope 11, chill members 23a are given their freedom since the cope is so constructed as to encircle shoulders 44 on chills 23a. Chill members 23a may then be easily moved axially and radially away from the hub and its scallops by reason of the beveled parting line 32 dividing chill members 23a and 24a, and also due to the fact that each chill member 23a straddles only one spoke as has been hereinbefore more fully referred to. After members 23a have been taken out between the spokes, chill members 24a may be displaced axially away from the scallops formed on the hub thereby, clearing the same, and being then removed from the space between the inner and outer sets of spokes. Obviously chills 23a and 24a may readily be dislodged by rapping the wheel after it is lifted from the drag and the cope is removed.

In order to prevent the formation of an outwardly projecting fin along the parting line 32 during the casting of the hub, the internal diameter of the chill 23 is preferably made slightly less than the internal diameter of the chill 24, see Figure 1. The result of the foregoing is to form a small beveled shoulder 55 between the upper portion of the hub H formed by chills 23a, and the lower portion thereof formed by chills 24a, with the cope end of the hub of smaller diameter. In this manner the formation of an objectionable shoulder, due to slight misalignment of the upper and lower chills, which would obstruct axial movement of chills 24a, is prevented, thereby assuring free axial movement of the chills 24a in disassembling the mold after the same has been cast.

When it becomes necessary to cast a hub on a wheel having an odd number of spokes the process will be exactly the same. The only variation in the construction of the mold will be in the chill section 23. This section will be composed of the same chill members 23a, each of the latter straddling one spoke and extending to the mid-points of the next adjacent spokes, but an additional chill member 45 will be required that will only extend between any two adjacent spokes, reaching from the mid-point of one to the mid-point of the other as best illustrated in Figure 9.

While I have shown what I regard to be

the preferred manner of practicing my invention it will be understood that such is merely exemplary and that other practices and constructions may be adopted within the broader aspects of the invention.

What I claim is:

1. In a mold for casting a scalloped hub on a wheel having its outer and inner sets of spokes initially assembled with the rim, and wherein the free ends of said spokes are adapted to be embedded within the scallops of the finished hub, the combination of a cope, a drag, a center core extending between said cope and drag, a first means carried by said drag and disposed about said center core, a second means mounted adjacent said first means and also disposed about said center core, said first and second means cooperating to support the free ends of one set of spokes in fixed relation within the mold cavity, and a third means seated upon said second means and disposed about the center core, said third means cooperating with said cope to support the free ends of the other set of spokes in fixed relation within the mold cavity, said first means and said cope being adapted to form the contour of the laterally outer extremities of the scalloped hub, respectively, said second and third means cooperating to form the outer contour of the portion of the scalloped hub that extends between the two sets of spokes.

2. In a mold for casting a scalloped hub on a wheel having its outer and inner sets of spokes initially assembled with the rim, and wherein the free ends of said spokes are adapted to be embedded within the scallops of the finished hub, the combination of a cope, a drag, a center core extending between said cope and drag, a lower chill member carried by said drag and disposed about said center core, a first intermediate sectionalized chill mounted adjacent said lower chill member and disposed about said center core, the aforesaid lower chill member and said first intermediate sectionalized chill cooperating to support the free ends of one set of spokes in fixed relation within the mold cavity, a second intermediate sectionalized chill seated upon said first sectionalized chill and disposed about said center core, said second sectionalized chill and said cope cooperating to support the free ends of the other set of spokes in fixed relation within the mold cavity, said lower chill member and said cope being adapted to form the outer contour of the extremities of the scalloped hub, and said first and second sectionalized chills cooperating to form the outer contour of the portion of the scalloped hub that extends between the two sets of spokes.

3. In a mold for casting a scalloped hub on a wheel having its laterally outer and inner sets of spokes initially assembled with the rim, and wherein the free ends of said spokes

are adapted to be embedded within the scallops of the finished hub, the combination of a cope, a drag, a center core extending between said cope and drag, a lower chill member carried by said drag and disposed about said center core, a first intermediate sectionalized chill mounted adjacent said lower chill member and disposed about said center core, the aforesaid lower chill member and said intermediate sectionalized chill having cooperating recesses to receive the radially inner ends of one set of spokes in fixed relation within the mold cavity, a second intermediate sectionalized chill seated upon said first sectionalized chill and disposed about said center core, said second sectionalized chill and said cope having cooperating recesses to receive the radially inner ends of the other set of spokes in fixed relation within the mold cavity, and means carried by said drag to retain said first and second sectionalized chills in fixed relation to said center core.

4. In a mold for casting a scalloped hub on a wheel having its outer and inner sets of spokes initially assembled with the rim, and wherein the free ends of said spokes are adapted to be embedded within said scallops, the combination of a cope, a drag, a center core extending between said cope and drag, a lower chill carried by said drag and disposed about said center core, and two sets of intermediate cooperating sectionalized chills, one set being seated upon said lower chill and about said center core and cooperating with said lower chill to receive the free ends of one of the sets of spokes in fixed relation within the mold cavity and the other set of sectionalized chills cooperating with said cope to receive the free ends of the other set of spokes in fixed relation within the mold cavity, said two sets of sectionalized chills adjoining each other on an inclined junction line, the inclination of which, relative to the axial center line of the wheel, is at least as great as the inclination of the spokes in one set of spokes relative to said axial center line.

5. In a mold for casting a scalloped hub on a wheel having its outer and inner sets of spokes initially assembled with the rim, and wherein the free ends of said spokes are adapted to be embedded within said scallops, the combination of a cope, a drag, a center core extending between said cope and drag, a lower chill mounted in the drag and disposed about said center core, and an adjacent pair of cooperating sectionalized chills seated upon said lower chill in spaced relation to said center core, one of said sectionalized chills and the cope having cooperating means to position the free ends of one of the sets of spokes in fixed relation within the mold cavity, said sectionalized chill having abutting engagement with said cope on a parting surface lying in the transverse plane of the centers of said one set of spokes, the

- other of said sectionalized chills having means cooperating with said lower chill to position the free ends of the other set of spokes in fixed relation within the mold cavity and having abutting engagement with said lower chill on a parting surface lying in the transverse plane of the centers of said other set of spokes, said pair of sectionalized chills adjoining each other on an inclined junction line the inclination of which, relative to the axial center line of said wheel, is at least as great as the inclination of any spoke in one of the adjacent sets of spokes relative to the same axial center line.
- 15 6. In a mold for casting a scalloped hub in a wheel having its outer and inner sets of spokes initially assembled with the rim, and wherein the free ends of said spokes are adapted to be embedded within said scallops, the combination of a cope, a drag, a center core extending between said cope and drag, a lower chill mounted in said drag and disposed about said center core, and two sets of sectionalized chills disposed about the center core and having means cooperating with said cope and said lower chill member, respectively, to receive the free ends of the inner and outer sets of spokes within the mold cavity, one of said sets comprising at least two chill pieces and the other set comprising at least half as many chill pieces as the number of spokes in one set of spokes, the chill pieces of one set being adapted to join the chill pieces of the other set on an inclined junction line the inclination of which, relative to the axial center line of said wheel, is at least as great as the inclination of the spokes in one set of spokes relative to said axial center line.
- 30 7. In a mold for casting a scalloped hub on a wheel having its outer and inner sets of spokes initially assembled with the rim, and wherein the free ends of said spokes are adapted to be embedded within said scallops, the combination of a cope, a drag, a center core extending between said cope and drag, a lower chill member disposed about said center core and supported on said drag, a pair of intermediate chill sets each comprising a plurality of chill pieces supported upon said lower chill member in spaced relation to said center core, said cope cooperating with the first of said intermediate chill sets to receive the free ends of one set of spokes in fixed relation within the mold cavity and having means engageable with the separate chill pieces of said first intermediate chill to prevent axial displacement of said pieces, the second of said intermediate chill sets cooperating with said lower chill member to support the free ends of the other set of spokes in fixed relation within the mold cavity, said first and second intermediate chill sets having abutting engagement along a downwardly and outwardly inclined junction surface to allow the removal of said
- 35 8. In a mold for casting a scalloped hub on a wheel having its outer and inner sets of spokes initially assembled with the rim, and wherein the free ends of said spokes are adapted to be embedded within said scallops, the combination of a cope, a drag, a center core extending between said cope and drag, a lower chill member supported concentrically to said center core by said drag, a pair of intermediate chill sets each comprising a plurality of chill pieces supported upon said lower chill member concentrically to said center core, said cope cooperating with one of said intermediate chill sets to receive the free ends of one set of spokes in fixed relation within the mold cavity and having means engageable with the separate chill pieces of said one chill set to prevent radial displacement of said pieces, the second of said intermediate chill sets cooperating with said lower chill member to receive the free ends of the other set of spokes in fixed relation within the mold cavity, said chill sets having abutting engagement along a downwardly and outwardly inclined junction surface to allow removal of said one chill set and whereby the chill pieces of said one chill set are adapted to hold the chill pieces of the second set against radial displacement, locking means including arms carried by said drag and releasably connected with said cope to positively lock all of said chill elements against separation axially of the wheel, and cooperative means carried by said lower chill member and drag respectively for positioning the mold parts and wheel spokes so as to allow the arms of said locking means to clear the spokes.
- 40 9. In a mold for casting a scalloped hub on a wheel having its outer and inner sets of spokes initially assembled with the rim, and wherein the free ends of said spokes are adapted to be embedded within the scallops of the finished hub, the combination of a cope, a drag, a center core extending between said cope and drag, a lower chill supported by said drag concentrically with said center core, a lower intermediate chill set supported adjacent said lower chill, and an upper intermediate chill set supported between said cope and said lower intermediate chill set, each of said intermediate chill sets comprising a plurality of chill pieces with the pieces of one set adjoining the pieces of the other set on an inclined junction line the inclination of which, relative to the axial cen-

chills and whereby the chill pieces of said first intermediate chill are adapted to hold the chill pieces of the second intermediate chill against radial displacement when the mold is locked, and locking means carried by said drag and releasably connected with said cope to positively lock all of said chill pieces and chill members against separation axially of the wheel.

45 8. In a mold for casting a scalloped hub on a wheel having its outer and inner sets of spokes initially assembled with the rim, and wherein the free ends of said spokes are adapted to be embedded within said scallops, the combination of a cope, a drag, a center core extending between said cope and drag, a lower chill member supported concentrically to said center core by said drag, a pair of intermediate chill sets each comprising a plurality of chill pieces supported upon said lower chill member concentrically to said center core, said cope cooperating with one of said intermediate chill sets to receive the free ends of one set of spokes in fixed relation within the mold cavity and having means engageable with the separate chill pieces of said one chill set to prevent radial displacement of said pieces, the second of said intermediate chill sets cooperating with said lower chill member to receive the free ends of the other set of spokes in fixed relation within the mold cavity, said chill sets having abutting engagement along a downwardly and outwardly inclined junction surface to allow removal of said one chill set and whereby the chill pieces of said one chill set are adapted to hold the chill pieces of the second set against radial displacement, locking means including arms carried by said drag and releasably connected with said cope to positively lock all of said chill elements against separation axially of the wheel, and cooperative means carried by said lower chill member and drag respectively for positioning the mold parts and wheel spokes so as to allow the arms of said locking means to clear the spokes.

50 9. In a mold for casting a scalloped hub on a wheel having its outer and inner sets of spokes initially assembled with the rim, and wherein the free ends of said spokes are adapted to be embedded within the scallops of the finished hub, the combination of a cope, a drag, a center core extending between said cope and drag, a lower chill supported by said drag concentrically with said center core, a lower intermediate chill set supported adjacent said lower chill, and an upper intermediate chill set supported between said cope and said lower intermediate chill set, each of said intermediate chill sets comprising a plurality of chill pieces with the pieces of one set adjoining the pieces of the other set on an inclined junction line the inclination of which, relative to the axial cen-

- ter line of the wheel, is at least as great as the inclination of the spokes in one set relative to said axial center line, said cope having openings disposed in registry with corresponding openings contained in the chill pieces of said upper intermediate chill set to receive the free ends of one set of spokes in fixed relation within the mold cavity, and said lower chill having openings disposed in registry with corresponding openings contained in the chill pieces of said lower intermediate chill set to support the free ends of the other set of spokes in fixed relation within said mold cavity.
10. In a mold for casting a scalloped hub on a wheel having its outer and inner sets of spokes initially assembled with the rim, and wherein the free ends of said spokes are adapted to be embedded within the scallops of the finished hub (the combination of a cope, a drag, a center core extending between said cope and drag, a lower chill supported by said drag concentrically with said center core, a lower intermediate chill set supported adjacent said lower chill, and an upper intermediate chill set supported between said cope and said lower intermediate chill set, each of said intermediate chill sets comprising a plurality of chill pieces with the pieces of one set adjoining the pieces of the other set on an inclined junction line the inclination of which, relative to the axial center line of the wheel, is at least as great as the inclination of the spokes in one set relative to said axial center line, said cope having openings disposed in registry with corresponding openings contained in the chill pieces of said upper intermediate chill set to receive the free ends of one set of spokes in fixed relation within the mold cavity, the chill pieces of said upper intermediate chill set having recesses formed therein in direct alignment with the cope openings for cooperating with said cope to form the scallops about the ends of the spokes supported between said cope and upper intermediate chill, said lower chill set having openings disposed in registry with corresponding openings contained in the chill pieces of said lower intermediate chill to receive the free ends of the other set of spokes in fixed relation within said mold cavity, said lower chill and the lower intermediate chill pieces being provided with recesses formed therein in direct alignment with their respective spoke openings to form the scallops about the ends of the spokes supported between said lower chill and the lower intermediate chill pieces.
11. In a mold for casting a scalloped hub on a wheel having its outer and inner sets of spokes initially assembled with the rim, and wherein the free ends of said spokes are adapted to be embedded within said scallops of the finished hub, the combination of a cope, a drag, a center core extending between said cope and drag, a first means carried by said drag and having recesses adapted to form one end of the scalloped hub, said cope having recesses adapted to form the other end of the scalloped hub, and a second means cooperating with said cope and said first means to receive the free ends of the two sets of spokes in fixed relation within the mold cavity with the ends of the spokes in one set disposed in spaced relation to the ends of the spokes in the other set, said second means having recesses adapted to form the contour of the scalloped hub extending between the two sets of spokes and comprising an upper chill set and a lower chill set disposed adjacent said upper chill set, said chill sets each having a plurality of chill pieces, each of the chill pieces of one of said sets being of such a peripheral length as to straddle one spoke of one set of spokes and to extend to the mid-points of the next adjacent spokes of that set whereby each of the latter chill pieces may be radially removed from the mold in the axial direction of the spokes straddled thereby after the hub is cast.
12. In a mold for casting a scalloped hub on a wheel having its outer and inner sets of spokes initially assembled with the rim, and wherein the free ends of said spokes are adapted to be embedded within the scallops of the finished hub, the combination of a cope, a drag, a center core extending between said cope and drag, a first means carried by said drag and having recesses adapted to form one end of the scalloped hub, said cope having recesses adapted to form the other end of the scalloped hub, and intermediate means cooperating with said cope and said first means to receive the free ends of the two sets of spokes in fixed relation within the mold cavity with the ends of the spokes in one set disposed in spaced relation to the ends of the spokes in the other set, said intermediate means having recesses adapted to form the contour of the scalloped hub extending between the two sets of spokes, said intermediate means comprising an upper chill member and a lower chill member disposed adjacent said upper chill member, said chill members each having a plurality of chill pieces adjoining the chill pieces of the other chill member on an inclined junction surface to enable the chill pieces of one of said members to be moved substantially axially of the mold and away from the adjacent set of spokes, each of the chill pieces of said one member being of a peripheral length so as to straddle one spoke of the adjacent set of spokes and to extend to the mid-points of the next adjacent spokes of that set to enable the chill pieces of said one member to be moved substantially radially in conjunction with the aforesaid axial movement thereof.

whereby the chill pieces of said one member may be removed from the mold into the space between the two sets of spokes to allow the balance of the mold elements to be dismantled after the hub is cast.

13. In a mold for casting a scalloped hub on a wheel having its outer and inner sets of spokes initially assembled with the rim, and wherein the free ends of said spokes are 10 adapted to be embedded within said scallops of the finished hub, the combination of a cope, a drag, a center core extending between said cope and drag, a first means supported adjacent said drag and having a surface 15 adapted to form one end of the scalloped hub, said cope having a surface adapted to form the other end of said scalloped hub, and a second means cooperating with said cope and said first means to receive the free ends of 20 the two sets of spokes in fixed relation within the mold cavity with the ends of the spokes in one set disposed in spaced relation to the ends of the spokes in the other set, said second means having surfaces adapted to form the 25 contour of the scalloped hub extending between the two sets of spokes and comprising two coacting sectionalized chill sets, the chills in one of said sectionalized chill sets being removable from the mold into the space between the two sets of spokes whereby the 30 balance of the mold may be disassembled after the hub is cast.

14. In a mold for casting a scalloped hub on a wheel having its outer and inner sets of 35 spokes initially assembled with the rim, and wherein the free ends of said spokes are adapted to be embedded within the scallops of the finished hub, the combination of a cope, a drag, a center core extending between said cope and drag, said drag being adapted 40 to form one end of the scalloped hub and movable axially of the wheel after the hub is cast, said cope being adapted to form the other end of said scalloped hub and being 45 movable axially of the wheel after the hub is cast, and a pair of superimposed chill sets disposed about the center core and between the free ends of the outer and inner sets of 50 spokes and cooperating with said cope and said drag to receive the free ends of the two sets of spokes in fixed relation within the mold cavity, the chills of said sets having surfaces 55 adapted to form the outer contour of the hub extending between said two sets of spokes, one of said sets having a plurality of chill pieces, and the second set having at least two chill pieces, the chill pieces of said first set adjoining the chill pieces of the second set on 60 an inclined injunction line whereby the chill pieces of said first set are movable out of the mold axially and radially of the wheel after the scalloped hub is cast, one of said sets of chills having a smaller internal diameter than 65 the other of said sets to allow removal of the

chill pieces of said other set in a direction axially of the wheel after the hub is cast.

15. A mold for casting a unit having a pair of members disposed in spaced relation along the axis thereof, said members projecting radially therefrom and converging outwardly toward each other, said mold comprising a cope and a drag to form the end portions of said unit, and cooperable means held between the cope and the drag and adapted to form the intermediate portion of said unit extending between said projecting members of the latter, said cooperable means each comprising a plurality of sections, the sections of one means being initially movable axially and radially outwardly of said mold whereby they are moved axially away from one of said members and radially away from said finished unit, the sections of said other means being thereafter movable axially of the mold away from the other of said members and then movable outwardly of the mold and free of said finished unit. 70 75 80 85

16. A mold for casting a unit having a pair of flange members disposed in spaced relation along the axis thereof, each of said flange members being provided with elements formed on their adjacently disposed faces and extending radially of said unit, said mold comprising a cope and a drag to form the end portions of said unit, and cooperable means held between the cope and drag and adapted to form the intermediate portion of the unit including said radially extending elements, said cooperable means each comprising a plurality of sections, the sections of one means being of such length as to completely form one of said elements and to extend to the mid-points of the next adjacent elements, said sections of said one means each 90 95 100 105 being movable radially outwardly of the mold in a direction along the one complete element formed thereby after said unit is cast.

17. A mold for casting a unit having a pair of flange members disposed in spaced relation along the axis thereof, said mold comprising a cope and a drag to form the end portions of said unit, and cooperable chill means held between the cope and the drag and adapted to form the intermediate portions of said unit extending between said flange members, one of said chill means having an internal diameter less than the internal diameter of the other chill means, said cooperable chill means each comprising a plurality of sections, the sections of said one cooperable chill means being radially movable out of said mold after said unit is cast. 110 115 120 125

18. A mold for casting a unit having a pair of flange members disposed in spaced relation along the axis thereof, said mold comprising a cope and a drag to form the end portions of said unit, and cooperable chill means held between the cope and the drag and adapted to form the intermediate por- 130

tion of said unit extending between said flange members, said cooperable chill means each comprising a plurality of sections, the sections of one cooperable chill means being radially movable out of said mold after said unit is cast and the sections of the other chill means being movable axially before they are removed from the cast unit.

In witness whereof, I hereunto subscribe
10 my name this 30 day of December, 1930.
WILLIAM A. HYLAND.
